UNITED STATES PATENT OFFICE.

ELIJAH H. COLE, OF BROOKLYN, NEW YORK.

BASEBALL GAME.

Application filed November 8, 1923. Serial No. 673,576.

To all whom it may concern:

Be it known that I, ELIJAH H. COLE, a citizen of the United States, and a resident of the city of New York, borough of Brooklyn, in the county of Kings and State of New York, have invented a new and Improved Baseball Game, of which the following is a full, clear, and exact description.

This invention relates to a baseball game-board and method of playing the game. An object of the invention is to provide a simple and interesting form of board and method of playing a baseball game whereby an unusually realistic game of ball can be played, including the possibility of all plays which occur in a regular baseball game, and also including the necessity for considerable skill on the part of the players.

The invention is illustrated in the drawings, of which—

Figure 1 is a plan view of the board; and Figure 2 is a section taken on the line 2—2 of Figure 1.

The form of the invention shown in the drawings is a preferred form, although it is understood that modifications in the construction and arrangement of the parts and in the character of the materials used may be adopted without departing from the spirit of the invention as set forth in the appended claims.

In general, the game includes a board on which a playing field is marked with the usual base lines and base sections, pitcher's box, catcher's box, etc. At the home plate there is provided a projecting portion in the form of a pin. In playing the game, the game piece, preferably a circular disk, is projected along the surface of the board from the pitcher's box by one of the players toward the pin, the object being to make it hit the pin and rebound from said pin in such a direction as will bring it back on the playing field, either the infield or the outfield. The board is provided with a plurality of designated areas representing certain types of plays, and when the game piece comes to rest in any one of these areas the play designated is put into effect.

The surface of the board is also provided with a number of depressed areas in which the game piece may come to rest. These depressed areas are located at the bases.

Back of the second base at the end of the board opposite the home plate, I provide a group of areas, successively more distant

from the home plate, which I call zones, representing one, two and three base hits and home runs. If the game piece comes to rest in any of these areas, the play may be either a clean base hit or a high fly caught by the fielder. Provision is also made for taking account of foul balls and flies, wild throws and wild pitches. In fact, practically every play which takes place in an ordinary ball game is accounted for in the operation of this gameboard.

The preferred form of the gameboard shown in the drawings has a base 1 provided with relatively shallow side walls 2^a. On the board is marked the usual playing field with the base lines 2, 3, 4 and 5, and with a projecting pin 6 at the home plate. At the first base there are disposed three defined areas 7, 8 and 9, the former being sunken. In line with the first base line and extending therebeyond to the wall of the board is a partition 10. Similarly, in line with the third base line and extending beyond the third base to the wall of the board is a partition 11. There is a recess 12 at second base and defined areas 13, 14 and 15 at third base, the former, 13, being sunken. There are also defined areas on the second and third base lines, designated by the numerals 16 and 17. There is also a defined area 18 disposed in the infield between the pitcher's box 19 and the home plate.

Extending from the second base outwardly toward the end of the board opposite the home plate are a plurality of groups of areas, said groups being numbered 20, 21, 22 and 23. These are marked on the surface of the board with characters which will be explained hereinafter. On the other end of the board adjacent the home plate are a plurality of areas 24, 25, 26, 27, 28, 29, 30 and 31. The game is played with game pieces such as 32 and 33, one of which is used to project from the pitcher's box toward the pin 6, and the other of which is placed back of the pin 6 in the area 31, supposed to be the batter, and disposed in position usually occupied by the catcher.

In the operation of the game there are two teams of one or more players each. One team, called the "inside," is supposed to be at bat; and the other team, called the "outside," is supposed to be in field. In starting the game the inside places the game piece in the batting circle, and the outside places a game piece in the pitcher's box and then

shoots it toward the projection 6; otherwise called the "batting pin." The game piece when projected toward the batting pin 6 will rebound therefrom in any one of many 5 directions in accordance with the angle at which it hits the pin, and it is dependent upon the skill of the pitcher to what point the game piece is deflected. If it goes into the field but outside the foul lines, then it 10 is a foul; and since the outside shot the piece the fouls are called balls. Then the inside shoots the piece at the pin and if it goes foul the first two fouls are called strikes. This continues alternately until the batter is out 15 or the man gets his base.

A man gets on the base when the ball is hit fair and does not get into any of the fly squares. In this case the outside player has a chance to shoot the game piece to the 20 particular base toward which the runner is running, but if he projects the piece into, for instance, the recess 7 at first base without having the game piece overlap the sides of the recess, then the runner is out, otherwise he is safe. If the game piece projected by the inside at the pin has been deflected into any of the areas marked foul fly, fly or 25 line fly then the runner is automatically out if the piece is located squarely within any 30 one of said areas. If the man is safe on his base, the inside puts a player piece on the base line nearest to the base which the runner has secured. If the game piece happens to be deflected into the wild throw 35 area such as 24, 25, 28 and 29, then the outside has made an error and the runner is entitled to another base. In the event that he wishes to try for more than one base he 40 may do so but in this case the outside has an opportunity to shoot a game piece to the base recess toward which the runner is moving to try to shoot him out. Whenever 45 the game piece is deflected to become a hit the batter can always try for more bases than he is entitled to, but in this case he takes a chance of being shot out by the other side.

With a man on second and third bases, a 50 one base hit would entitle both the players to come home safe.

If the game piece is deflected into any one of the zone areas 20 to 23, inclusive, the play is determined in accordance with the 55 area in which the piece is located. For instance, if the piece is located in the first base zone in one of the areas marked hit then the player has a safe one base hit. If, however, the piece lands in the area in this zone marked fly then the player is out. 60 On the other hand, if the piece lands in an area in the zone 20 which is a blank, then the player has made a good hit but in this case the outside can shoot a piece to the first base and try to shoot the runner out 65 by making the piece land in the recess 7.

The second base zone 21, the third base zone 22, and the fourth base zone 23 are marked in a similar manner and the plays take place in a similar manner, as the game piece may land in any one of these further 70 zones. In accordance with the rules of the game, all flies in the third and fourth zones 22 and 23 are sacrifice flies and the runner who happens to be on third base can come home safe. 75

To try a single, double or triple steal, the inside must move the runner only and just before the outside shoots at the batting pin. The outside is then allowed a free 80 shoot from the place the game piece lands to any base to try to get the runners out. The play of catching a man off base can be tried if the inside fails to move a runner back to the base when the outside shoots at the batting pin, and the outside is allowed 85 a free shoot from the place the ball lands to get the man out, if he desires.

In making double play, this is only effected on balls to the infield. Whenever a 90 bunt occurs the ball is shot to the base to which the runner is forced. If the runner is out the game piece is then shot to first base, or, if the play is a fly, the piece is shot to the nearest base on which there is a runner. On a force-out, which means that 95 the ball is batted to the base square on which there is a runner, the piece can then be shot to any other base square or recess to make another out.

A triple play is only allowed to be made 100 when the game piece goes to either the areas 16 or 17, marked line fly. The game piece must then be shot to the bases on which the two runners are located.

A runner on third can try for home plate 105 on a two-base fly, but the outside can try to shoot him out. In shooting the home plate, if the game piece hits the batting pin or goes into the catcher's space the runner is out, the catcher's space being the 110 square 31.

On a fly to third or fourth base zone a 115 runner on first or second can try to advance, but the outside has the privilege of shooting him out if possible. Similarly, a man on first can try for home on a two base hit with the possibility of being shot out.

If there is a man on first and one on third 120 the inside may try a double steal, in which case they move the runner just before the outside shoots at the batting pin. If the play is a "ball," the outside shoots it at the second base, and if it goes into the second base recess 12, he can take his choice on having that runner out or shooting it back to the home plate to try for the runner getting home. In this case, if the ball does not go 125 into the second base recess 12, he can try for home, unless the piece goes beyond the 130

second base line in which case both runners are safe and the outside has made a wild throw.

If the play is an infield fair ball, the outside can play it home or play it to second and then to first, making two out, but in that case the runner on third has scored even if it makes three out. If the play is a fair ball to the out field, the outside can play it to second base or to first base unless it is in the one base zone, in which case he must play it to first base, making both the man going home and the man going to second safe, unless there happens to be two out at the time.

In playing the game both sides should remember that the disk is called the "ball", and that the term "shooting" is used instead of throwing. The outside always shoots first at a new batter. The inside is the only side which can move the runners. The outside is the only side which can shoot to the base. The inside can shoot only at the batting pin from the pitcher's box. The outside can only shoot "balls", and the inside can only shoot "strikes". A ball or strike is made either by missing the batting pin or by going foul. Four balls or three strikes can only be called by missing the batting pin going up; all other tries are just "foul balls". A fair ball is one that rebounds from the batting pin into fair territory. A foul fly is out for either side.

Furthermore, double plays can only be made with the ball going to the infield. A triple play can only be made when the ball goes to the "line fly" square.

Whenever a wild throw is made by the outside in shooting to a base, all the runners are entitled to another base. Similarly, a wild pitch made by the outside entitles all runners to an extra base. Whenever a "balk" is made by the outside all runners are entitled to advance one base but the outside in this case does not lose his try at the batting pin. Any runner hit by a batted ball is out. Any batter hit by a pitched ball only by the outside can take his base. To be hit by a pitched ball the ball must not hit the batting pin going up. It will be noted that when a ball goes into foul territory it is prevented from rebounding from the side walls 2 into fair territory by reason of the interposition of the partitions 10 and 11.

It will, therefore, be observed that in the operation of this game and in the use of

this board practically every play in an ordinary baseball game can occur. It will also be observed that considerable skill is required to produce the desired plays, both in shooting at the batting pin and causing the piece to rebound in the right direction, as well as in shooting to the base recesses.

What I claim is:—

1. A baseball game apparatus which comprises a playing surface on which a baseball diamond is marked off, a projecting pin at the home plate against which a game piece is adapted to be projected to rebound therefrom in any direction in accordance with the skillful effort of the player projecting the piece, said surface being provided with a depressed area at the first, second and third base positions to receive an outfield game piece projected thereto from any part of the field for the purpose of putting out the runner, said board also provided with foul and fair fly areas at the first and third bases to receive the game piece coming to rest thereon, as well as line fly areas intermediate the first, second and third base positions for the reception of game pieces coming to rest thereon.

2. A baseball game apparatus which includes a playing board on the surface of which a baseball diamond is marked, a projecting pin at the home plate against which a game piece is to be projected to rebound therefrom, a plurality of rows of areas marked on the board back of the second base, these areas arranged in rows at successively greater distances from the home plate, these areas representing one, two, three and four base hits in order, certain of said areas in each zone or group being marked to represent flies and others marked to represent safe hits.

3. A baseball game apparatus which includes a playing surface on which a baseball diamond is marked, a projecting pin at the home plate against which a game piece is adapted to be projected to rebound therefrom into other parts of the board, said board provided with a depressed area at the first, second and third base positions for the reception of the game piece as it rebounds, said board also being provided with a plurality of areas arranged in groups or zones back of the second base position, these areas marked to represent safe hits or flies in accordance with their distance from the home plate.

ELIJAH H. COLE.
